CLAIM

The ornamental design for a residential stove wrap, as shown and described.

DESCRIPTION

FIG. 1 is an upper perspective view of a residential stove wrap, illustrating the residential stove wrap in an example operating environment;

FIG. 2 is a top view or a bottom view thereof;

FIG. 3 is a side view thereof; and,

FIG. 4 is a front view or a rear view thereof.

The broken lines showing a stove form no part of the claimed design.
